HENRY W. STAPLES, OF NEW HAVEN, CONNECTICUT, ASSIGNOR, BY MESNE ASSIGNMENTS, TO WINCHESTER REPEATING ARMS COMPANY, A CORPORATION OF DELAWARE

BULB HOLDER FOR FLASH LIGHTS

Application filed October 10, 1928. Serial No. 311,423.

This invention relates to bulb holders for battery hand lamps.

In the usual construction of a battery hand lamp, a battery is arranged in a casing having a removable head and a lamp bulb is removably mounted in the end of the casing with the base terminal of the bulb in contact with the carbon pole of the battery. An electric circuit is completed from the zinc can of the 10 battery to the other terminal of the lamp through the lamp casing and the circuit is opened or closed by means of a switch mounted on the casing. The removable head of the lamp carries a reflector and lens which are arranged in front of the bulb when the parts are in position.

One of the chief objections to the present type of battery hand lamps is the liability of the bulb to become loose in the bulb holder or 20 socket and thus break the circuit at this point. If the bulb becomes loose, a circuit will not be completed when the switch is closed. This occurs frequently when a hand lamp is carried in the tool kit of an automobile, which is 25 one of the uses to which such hand lamps are put, but it also frequently occurs from other causes.

In the present invention I provide means for retaining the bulb in its holder or socket 30 preferably consisting of yieldable means engaging the bulb to retain it in its socket but to permit its removal when desired by application of sufficient force to overcome the yieldable means. I preferably employ a 35 threaded socket of the usual type having grooves or slots and provide a resilient retaining member having bowed or curved arms which are adapted to be arranged in said grooves or slots with a portion thereof normally projecting beyond the threads into the 40 path of the bulb when it is screwed into the socket. I may also provide suitable means for forcing the arms of the retaining member inwardly into the path of the bulb so that when 45 the bulb is screwed into its socket these arms will be placed under tension and securely hold the bulb in place.

In the accompanying drawings I have shown one form of the invention. In the 50 drawings,

Fig. 1 is a longitudinal, sectional view through the upper end of a battery hand lamp showing the invention applied;

Fig. 2 is a similar view of the bulb holder or socket on an enlarged scale;

Fig. 3 is a view similar to Fig. 2 taken at right angles thereto on line 3-3 of Fig. 2;

Fig. 4 is a horizontal, sectional view on line 4-4 of Fig. 2; and

Fig. 5 is a side elevation of the spring retaining member.

Referring to the drawings, the reference numeral 1 designates generally a hand lamp casing of the usual construction. This casing is adapted to receive a battery, the upper end of which is shown at 2. The end of the casing is threaded in the usual manner as indicated at 3 and is adapted to receive an end cap 4 which is likewise provided with threads 5 adapted to engage the threads 3 to permit the end cap to be placed in position and removed. A head 6 is mounted on the end cap, being secured thereto by means of threads 7 and this head is adapted to clamp a lens and a reflector 8 in position. In the form of the invention shown the lamp socket is carried by the reflector, but it will be understood that this is merely illustrative and that the lamp socket may be carried by a separate supporting member as is now used in various types of battery hand lamps in which the reflector and bulb are adjustable with respect to each other for focusing purposes. As shown, the lamp socket 9 is received in a central opening in the reflector and is provided with a circular band or flange 10 which is adapted to be turned over as shown in Fig. 1 of the drawings to clamp the socket to the reflector. The socket is generally cylindrical in shape and adjacent the lower end thereof, it is internally threaded as at 11 for the reception of the threaded portion 12 of lamp bulb 13. The upper portion of the lamp socket is preferably of greater diameter than the lower portion as indicated at 14, forming a shoulder 15 intermediate the top and bottom of the socket.

The retaining means forming the subject matter of this invention is adapted to be supported on the shoulder 15 and preferably comprises a split resilient ring 16 which may

be seated on this shoulder and is out of the path of the bulb as will be clearly apparent from Fig. 1 of the drawings. This ring is provided with depending arms 17 which are 5 adapted to be received in grooves or slots 18 in the threaded portion of the socket and which depend from the ring 16. As shown, the arms 17 are bowed or curved so that a portion thereof will project inwardly toward the center of the socket beyond the walls of 10 the threads.

To urge the retaining arms inwardly, I may employ a cup-shaped member 19 adapted to fit over the lower end of the lamp socket 15 and be retained thereon by friction. The wall of this member may be provided with a slot 20 to permit it to be sprung into position over the exterior of the lamp socket. The function of the cup-shaped member is to engage the lower ends 21 of the arms 17 forcing them inwardly and causing the bowed portion of the arms to project beyond the threads as shown in Fig. 2 of the drawings. In some instances the use of the cup-shaped member 20 may be dispensed with and the bulb, when in position, will then assume such position that its base terminal will engage the carbon pole of the battery. However, when the cup-shaped member 19 is employed I provide 25 suitable means for forming a connection from the base terminal of the bulb to the carbon pole of the battery and as shown I provide an opening 22 in the bottom of the cup-shaped member in alignment with the base terminal 30 of the bulb. Discs of insulating material 23 are placed above and below the surface of the cup-shaped member and a disc of metal 24 is then placed over the outside disc of insulating material. These discs are secured 35 in position by means of a rivet 25 which completes the circuit from the carbon pole of the battery 2 to the lower terminal of the lamp bulb 13 as clearly shown in Fig. 1 of the drawings.

40 The operation of the device will be apparent from the foregoing description. When the lamp bulb 13 is screwed into the socket 11, the bulb contacts with the bowed portions of the arms 17 and as these arms are prevented from moving outwardly by the engagement of their lower ends 21 with the inner wall of the cup-shaped member, the movement of the bulb into the socket flexes these arms from the position shown in Fig. 2 45 of the drawings to the position shown in Fig. 1 of the drawings and places them under tension. The bulb is thus retained in the lamp socket under tension at all times and this prevents its accidental displacement by vibration, but at the same time, does not prevent the removal of the bulb by the application of sufficient force to overcome the tension of the arms 17. The bulb may thus be unscrewed by the user of the battery hand lamp 50 in the usual manner.

I claim:

1. A bulb holder comprising a socket, the wall of said socket being provided with a groove, a resilient retaining member mounted in said groove and having a portion normally projecting into the central bore of said socket, and an annular member surrounding said socket and engaging said resilient member to retain it in operative position. 70

2. A bulb holder comprising a threaded socket body of insulating material having a plurality of grooves parallel to its axis, a ring seated in said socket, and curved resilient arms carried by said ring having portions disposed in said grooves and portions normally projecting into the bore of said socket, and means for retaining said arms in operative position. 75

80

3. A connecting member for a lamp bulb socket of a battery hand lamp comprising a cup-shaped member carried by said socket and adapted to surround the portion of the bulb projecting beyond the bottom of the socket, a connecting member extending through the bottom of said cup-shaped member and adapted to establish electrical connection between the base terminal of a lamp bulb and the carbon pole of a battery when the parts are in assembled position, and means for insulating said connecting member from the body portion of said cup-shaped member. 85

90

4. A bulb holder for battery hand lamps comprising a threaded socket, the upper portion of said socket being of greater diameter than said threaded portion and forming a shoulder, the threaded walls of said socket being provided with grooves, a ring seated on said shoulder, arms carried by said ring and arranged in said grooves with portions thereof normally projecting into the bore of said socket, and means for retaining said arms in operative position. 100

105

5. A bulb holder for battery hand lamps comprising a threaded socket, the upper portion of said socket being of greater diameter than said threaded portion and forming a shoulder, the threaded walls of said socket being provided with grooves, a ring seated on said shoulder, arms carried by said ring and arranged in said grooves with portions thereof normally projecting into the bore of said socket, a cup-shaped member mounted on the bottom of said lamp socket and engaging said arms to retain the projecting portions 110 thereof in operative position. 115

In testimony whereof I affix my signature.
HENRY W. STAPLES.
